DESIGN.

LA MARTINE FRENCH.

PIANO COVER.

No. 18,203.

Patented Mar. 27, 1888.

UNITED STATES PATENT OFFICE.

LA MARTINE FRENCH, OF CHICAGO, ILLINOIS.

DESIGN FOR A PIANO-COVER.

SPECIFICATION forming part of Design No. 18,203, dated March 27, 1888.

Application filed January 20, 1888. Serial No. 261,412. Term of patent 7 years.

To all whom it may concern:

Be it known that I, LA MARTINE FRENCH, of Chicago, Illinois, have invented and produced a new and original Design for Piano-
5 Covers for Upright Pianos, of which the following is a specification.

The nature of my design is fully represented in the accompanying photographs.

It consists in a shape or configuration bounded by certain lines, as will be hereinafter more fully set forth.

Figure 1 represents the appearance of the design on a piano. Fig. 2 represents the same, but with less margin at the center line, C.

15 In the figures, A is a continuous border-line bounding the top of the design. BB are par-

allel lines bounding the design at its ends and lower part. E represents lines converging inwardly and upwardly from BB toward the middle of the cover, and C is an interior connecting-line joining the lines E E.

I claim—

The design for a piano-cover herein shown and described, the same consisting of the shape or configuration bounded by the continuous border-line A, the parallel lines BB, the upwardly and inwardly converging lines E E, and the interior connecting-line, C.

LA MARTINE FRENCH.
